Inventor
Thomas A. Gerlach

By Gabel & Banning

UNITED STATES PATENT OFFICE.

THOMAS A. GERLACH, OF HARVEY, ILLINOIS.

SPRING SWITCH BOX.

Application filed May 28, 1928. Serial No. 281,322.

My invention relates to spring switches, and more particularly to reversible spring throws and switch locks for tongue switches.

One of the objects of this invention is to 5 simplify the construction thereof so that the parts can be readily taken out and replaced when necessary.

Frequent inspection is usually necessary on 10 these devices, since they are exposed to the mud and ice and are generally not mounted in water-tight boxes. This makes it necessary to provide a device which is readily accessible, and where the traffic is heavy to so construct the device that the parts thereof may be with- 15 drawn and replaced easily.

My invention contemplates the provision of 20 a device of this character similar to that shown in my prior Patent No. 995,341, issued June 13, 1911, with certain improvements 25 whereby the device may be more readily used as an anti-kicker.

Another purpose of this invention is to 30 provide a device of this character in which the switch may be thrown by the use of an operating handle, generally carried by the motorman of the car, without removing the cover of the mechanism, and without the use 35 of any great amount of force. This is due to the fact that in this device when the motor- 40 man throws the switch his efforts are not used in compressing the spring.

A further and more particular purpose of 45 the invention is to provide a device of this character in which all the parts can be taken apart and put together without the necessity of turning a single screw or bolt and in which the parts are held in place by each other and by the cover.

Other objects and advantages of the in- 50 vention will appear as the description pro- 40 ceeds, in connection with the following draw- ings, in which one form of my invention is shown. However, it is to be distinctly under- 45 stood that I do not intend to limit myself to the exact details shown and described, but that I may avail myself of all such modifi- 55 cations as fall within the scope of the claims.

In the drawings,—

Fig. 1 is a vertical section showing my 50 device as applied to a tongue switch;

Fig. 2 is a plan view of the device;

Fig. 3 is a section on the line 3—3 of Fig. 4; and

Fig. 4 is a section on the line 4—4 of Fig. 3, with the operating member in a slightly 55 different position.

Referring now in detail to the drawings, in Fig. 1, I show two rails 5 and 6 and a switch tongue 7, which through the agency of the connecting rod 8 is designed to be operated by 60 my spring throw or switch lock device. This device is mounted in a casing 9 having the cover 10 fitting down within the top thereof and resting upon the ledges 11, 12 and 13.

Within the casing 9 there are provided 65 bearings 14 and 15 which are cast integral with the casing and extend upwardly from the bottom thereof to provide a bearing for a sliding member 16, which forms one of the 70 spring holding devices of the mechanism. The member 16, as shown, is turned up at its end and slotted, as at 17, to receive the end of 75 the connecting rod 8, which is provided with a pair of projections fitting on opposite sides of the upturned end of the member 16.

The bearings 14 and 15 are semicircular, so 80 that the member 16 may be rotated through substantially one hundred and eighty degrees when it is desired to remove the same from the connecting rod 8.

Another spring member 18 co-operates with 85 the member 16 to form a housing for the spring 19, and these two members, as shown in Fig. 2, are provided with interfitting portions 20 and 21, adjacent the opposite ends thereof, 90 which engage the spring, so that movement of either of the members 16 and 18 relative to the other effects a compression of the spring.

This construction is so far substantially 95 the same as that in my prior patent herein- before mentioned.

It will be noted from Fig. 2 also that the member 18 is guided, by means of the wings or projections 22, 22, between a plurality of 100 projections 23 and 24 on one side wall of the casing and on the partition 25 which extends lengthwise of the casing.

In this manner the spring and the spring 105 housing members 16 and 18 may be mounted and held in place within the casing without the use of screws or bolts. The member 18 has on the top thereof a projection 26 which is provided with a slot 27 to receive the crank 28 in a manner similar to that shown in my prior 110 patent. This crank 28 has one end 29 seated in a recess 30 found in the side wall of the

casing, and the other end of the crank has a bearing provided by the slot 31 in the partition 25.

Thus, after the members 16 and 18 are in position with respect to the spring 19, the crank 28 may be put in position by dropping the free end of the crank into the slot 31 and then pushing the end 29 into the recess 30. The crank is provided, where it extends beyond the partition 25, with a small pinion 32, by which the crank is adapted to be rotated to move the spring member 18 and throw the switch. Cooperating with the gear 32 is the pivoted member 33 having the quadrant gear 34 thereon, which fits down over the pinion 32 and serves to rotate the pinion, as well as to hold the crank down in its slot 31. Member 33 fits loosely upon the pin 35, which is preferably a steel pin cast integral with the box or casing.

In assembling the device, after the crank has been placed in position as hereinbefore described, the member 33 is slid over the end of the pin 35 so that the quadrant gear 34 engages with the pinion 32 in substantially the position shown in Fig. 4. As the member 33 fits loosely on the pin 35, it would not remain in this position were it not for the cover 10. This cover, as shown in Fig. 3, however, is provided with a slot 36, into which the upper portion of the member 33 projects, so that when the member 33 is mounted and the cover in position, the cover itself holds the member 33 from slipping off the pin 35. The cover is also cut away, as at 37 and 38, to accommodate the top of the quadrant gear 34 and the crank, so as to save space and make a device of as small a depth as possible. The cover has also cast integral therewith a depending lug 39, which extends down along the outer face of the member 33 to provide a wide bearing surface that will hold the member 33 firmly in position and strengthen the cover at this point.

Thus it will be seen that the entire device is made up of parts which are assembled in a certain order and each one of which is held in place by the succeeding part in the steps of assembly, so that when finally the cover is placed in position all of the parts will be held in their proper position without the use of any bolts or screws. Also, upon removal of the cover, the parts may be readily taken apart and replaced without the use of any special tools, and this makes repairing easy.

However, if it is desired to use the device without a cover, a suitable distance piece may be inserted between the member 33 and the side wall of the box to hold the member 33 on the pin 35.

Now in operating the device to throw the switch, the motorman usually is provided with an iron bar about three to four feet long, which is of such size that it will fit in the recess 40 provided in the member 33 and enable

him to rock the member 33 in either direction he desires, which action will be communicated by means of the pinion 32 to the crank 28, and through this crank and the spring box construction to the connecting rod 8. The recess 40 at its lower end is opened out to the exterior of the member 33 as at 41 and 42 to prevent foreign matter or dirt from accumulating therein.

The gear teeth on the quadrant gear and pinion are preferably so made that for the length of stroke permitted by the slot 36 the crank 28 will be thrown through an angle of slightly more than one hundred and eighty degrees, so that in its resting position at either end the portion of the crank in the slot 26 will lie slightly below the center line of the bearings for the crank. This is done merely to cause the crank to have a tendency to resist any pressure upon the member 16 from throwing it into its opposite position, and serves as an effective locking device for holding the switch in whichever position it is moved by the motorman.

From the above description, it is thought the construction and operation of this device will be clear to those skilled in this art.

Having thus described my invention, what I claim as new and desire to secure by Letters Patent is:

1. A spring box for switches having a spring and spring members, a crank associated with one of said members and removably mounted in said box, and operating means for said crank removably mounted in said box and holding said crank in operative position within said box.

2. A spring box for switches having a spring and spring members, a crank associated with one of said members, bearings in said box in which said crank is removably mounted, and operating means for said crank holding said crank in said bearings.

3. A spring box for switches having a spring and spring members, a crank associated with one of said members, bearings in said box in which said crank is removably mounted, operating means for said crank holding said crank in said bearings, and a cover having means thereon for holding said operating member in position.

4. A spring box for switches having a spring and spring members, a crank associated with one of said members, bearings in said box in which said crank is removably mounted, operating means for said crank holding said crank in said bearings, and a cover having means thereon for holding said operating member in position, said cover having an aperture therein through which means may be inserted for moving said operating means.

5. A spring box for switches having a spring and spring members, a crank associated with one of said members, operating

means for said crank and a cover for said box, said cover holding said crank and operating means in assembled position.

6. A spring box for switches having a spring and spring members, a crank associated with one of said members, operating means for said crank and a cover for said box, said cover holding said crank and operating means in assembled position, said cover having an aperture therein permitting access to said operating means when the cover is in position.

7. A spring box for switches having a spring and spring members, a crank associated with one of said members, bearings in said box in which said crank is mounted, a

pinion on said crank, and a member rockably mounted in said box and having a plurality of gear teeth thereon engaging said pinion to rock said crank. 20

8. A spring box for switches having a spring and spring members, a crank associated with one of said members, bearings in said box in which said crank is mounted, a pinion on said crank, a member pivoted in 25 said box and holding said crank in its bearings, and gear teeth on said member engaging with said pinion.

In witness whereof, I hereunto subscribe my name this 18th day of May A. D., 1928.

THOMAS A. GERLACH.
